CLAIM

The ornamental design for a transparency viewer, substantially as shown and described.

DESCRIPTION

FIG. 1 is a top and right front perspective view of a transparency viewer showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and

FIG. 7 is a right side elevational view thereof.

The picture disclosed in FIGS. 1 and 2 represents a transparency which does not form a part of the article claimed.

FIG. 1

FIG. 2

FIG. 3
